UNITED STATES PATENT OFFICE.

PAUL E. VAN NOSTRAND, OF LYONS, NEBRASKA.

CAN OPENER.

Application filed November 6, 1923. Serial No. 673,195.

To all whom it may concern:

Be it known that I, PAUL E. VAN NOSTRAND, a citizen of the United States, residing at Lyons, in the county of Burt and 5 State of Nebraska, have invented new and useful Improvements in Can Openers, of which the following is a specification.

My present invention pertains to can openers, and it contemplates the provision of 10 a device through the medium of which a can or other receptacle may be readily and easily opened, and the portion of the can that is cut therefrom entirely removed from the can without coming into contact with the 15 fingers or hands of the operator.

The invention further contemplates the provision of a can opener that eliminates turning or twisting of the can during the opening operation, and at the same time one 20 that holds the can or other receptacle in a rigid manner during the cutting of the top or other portion from the can or receptacle.

The invention in all of its details will be 25 fully understood from the following description and claim, when the same are read in connection with the drawings, accompanying and forming part of this specification, in which:

Figure 1 is a top plan view of a can or 30 receptacle and showing my novel opener during the cutting operation.

Figure 2 is a longitudinal sectional view of the opener as positioned on a can.

Figure 3 is a detail vertical sectional view 35 taken in the plane indicated by the line 3—3 of Figure 2 and looking in the direction of the arrow.

Figure 4 is a bottom plan view of the 40 pivotal connection and center anchoring device.

Figures 5, 6, 7 and 8, are detail views of 45 component parts of the opener.

Similar numerals of reference designate 50 corresponding parts in all of the views of the drawings:

My novel opener comprises the upper handle 1 and the lower handle 2, that are each 55 provided at one end with the grips 3, and are pivoted with respect to each other through the medium of the element designated as a whole by 4. The pivotal member 4 comprises a head 6 having a shank portion 7 that is reduced at the point indicated by 8 that allows easy movement of parts and 60 prevents binding of the handles 1 and 2 after they have been pivotally mounted on the

member 4. A spacing washer 9 is arranged over the shank of the member 4 as shown.

Slidably mounted on the handles 1 and 2 are collars 10 and 11, and the said collars 60 are open at their upper ends, by preference, and the collar 10 is provided with the cutting blade 12 that is arranged at right angles with respect to the upper surface of the collar and as will be particularly noted 65 by reference to Figure 2, the cutting blade 12 is beveled on its edges and toward the handle grip 3 of the handle 1. This provision is made in order that even and positive cutting of the slot S of the can 70 will be assured. The provision is also made in order that during the cutting operation, the blade when so beveled will not be forced toward the center of the can but will cut in an approximate even circle at all times. 75

The collar 11 is provided with the blade 13 that is beveled on its outer surface. This blade 13 is arranged parallel with respect to the upper portion of the collar 11, and acts as an anchor. Its purpose being to puncture 80 and remain stationary in the top of the can. This stationary arrangement is due to the manner in which the blade 13 is beveled and revolving of the handle 1 will not pull or otherwise remove the blade 13 from its 85 anchored positions.

Interposed between the washer 9 and the blade 2 on the shank 7 of the pivot 4 is an anchor member 14 that is bent upon itself as indicated by 15 and is provided at its extreme outer end with the puncturing edge 16. This puncturing edge is so constructed 90 that the assembled device will pivot thereon and the said edge will at all times be the center of the arc described by the cutting 95 blade 12. The anchor member 14 is further provided with a slot 18 that terminates in the semi-circular seat 17 that surrounds the shank 7 when the device is assembled, and the said member 14 is also provided with the 100 downwardly turned end portions 19 that rest over the portion 20 of the handle 2 and firmly retain the handle 2 in proper position on the pivot.

It will be manifest that the handle portion 2 turns at all times synchronously with the pivotal member 14 on the pivot 4 and that the handle 1 is pivoted independently with respect to both the member 14 and handle 2. 105

In the practical use of the invention, the edge 16 is inserted into the center of a can,

and because of the manner and position at which the edge is arranged on the shank 7 with respect to the handles 1 and 2, operation of the handles will not dislodge the edge 5 16 from the top. The anchor 11 of the handle 2 is then thrust into the can near the edge thereof or at any point desired, and the blade 12 of the collar 10 on handle 1 is then forced into the top. The handle 2 is then 10 held stationary in one hand, and the grip 3 of the handle 1 moved so as to describe an arch to produce the slot S as illustrated.

The arrangement of the blade 13 on the inner side of the collar 11 enables the operator to cut a slot entirely around the can and when this had been done, raising of the handles will lift the cut out portion of the top from the can.

The invention is entirely capable of use 20 by any person without previous skill in operating same, and because of its construction and the arrangement of the beveled and piercing edges of the blades and anchor no strength whatever is required to open a can.

Having described my invention, what I 25 claim and desire to secure by Letters-Patent, is:

In a can-opener, the combination of two

pivotaly connected members, an anchor removably secured on the pivot of the members and comprising a body portion having a stud receiving aperture that terminates in an open mouthed slot; said body portion having down-turned ends adjacent the mouth of the slot and further having a piercing portion formed at its end away from its down-turned end, means for holding one of the pivotal members in stationary manner and comprising a collar adjustably movable on the stationary pivotal member and terminating in a cutting edge that is positioned parallel with respect to the stationary member, and cutting means slidably mounted on the movable pivotal member and comprising a collar that terminates in a cutting blade that has its edge beveled on the inner and outer surface and rests at a right angle with respect to the collar.

In testimony whereof I have hereunto set my hand in presence of two subscribing 50 witnesses.

PAUL E. VAN NOSTRAND.
